(57) **CLAIM**

The ornamental design for a skirt for a truck, as shown and described.

DESCRIPTION

1. Truck skirt

FIG. 1.1 is a perspective view of a truck skirt of the present application.

FIG. 1.2 is a front view of the truck skirt.

FIG. 1.3 is a back view of the truck skirt.

FIG. 1.4 is a top view of the truck skirt.

FIG. 1.5 is a bottom view of the truck skirt.

FIG. 1.6 is a left side view of the truck skirt.

FIG. 1.7 is a right side view of the truck skirt.

FIG. 1.8 is a perspective view illustrating the truck skirt on a truck shown in broken lines.

Broken lines in FIGS. 1.1-1.7 show portions of the truck skirt that form no part of the claimed design. Broken lines in FIG. 1.8 show environmental subject matter that forms no part of the claimed design.
